UNITED STATES PATENT OFFICE.

PARKER B. HASKELL, OF LYNN, MASSACHUSETTS, ASSIGNOR OF ONE-THIRD TO WALTER B. POHLE, OF LYNN, MASSACHUSETTS, AND ONE-THIRD TO SUSAN V. RUSSELL, OF CHELSEA, MASSACHUSETTS.

SEDIMENT REMOVER FOR SPLASH TROUGH.

Application filed February 6, 1925. Serial No. 7,331.

This invention relates to crank casings for internal combustion engines, and has for its object the provision of means whereby the sediment in the splash troughs may be quickly removed therefrom without removing the trough from the casing.

This object is attained by the mechanism illustrated in the accompanying drawing.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings:

Figure 1 represents a section of a portion of the crank casing of an internal combustion engine showing one of the splash troughs thereof and means for removing the sediment therefrom, embodying the principles of the present invention.

Figure 2 represents an end elevation of said trough, and

Figure 3 represents a transverse section on line 3, 3, on Fig. 1.

Similar characters indicate like parts throughout the several figures of the drawings.

In the drawings, 10 is a crank casing having a pan 11 at the bottom thereof.

The casing 10, as illustrated in the drawings, is adapted to contain a plurality of cranks 12 of an internal combustion engine, one of said cranks 12 being shown in Fig. 1 of the drawings as secured to a crank shaft 13 and having the usual connecting rod 14 pivotally secured to its free end.

Beneath each crank 12 is disposed an oil trough 15 having a compartment 15* adapted to be partly filled with oil through which the free end of the crank 12 must pass as the crank shaft 13 revolves, thereby thoroughly lubricating the bearings between the crank 12 and the connecting rod 14.

In another application of mine, Serial No. 732,741, filed August 18, 1924, is shown means whereby each of the oil troughs 15 may be removed from the casing without disturbing the other troughs.

In some cases it is desired to remove the oil troughs as seldom as possible and consequently it is desirable to provide some means coacting with each trough whereby the oil or sediment in the trough may be removed while the trough remains within the casing.

To accomplish this end, each trough 15 is provided with a passage 16 in the bottom thereof, the lower end of which communicates with a cylindrical chamber 17 extending lengthwise of said trough, said chamber 17 being closed at the inner end of the trough while the outer end thereof is threaded as at 18 and has screwed therein a closure 19.

Within the chamber 17 is positioned a cylindrical member 20 having a depression 21 in its upper side registering with the passage 16 and in which all sediment in the trough is adapted to collect.

The outer end of the member 20 is cone-shaped at 22 and has a projection 23 extending outwardly therefrom provided with a diametrical hole 24, adapted to receive a pin to assist in removing the member 20 from the chamber 17.

The cone-shaped end 22 fits into a cavity in the closure 19 and the projection 23 extends through said closure, all as shown in Fig. 1.

The member 20 has a groove 25 extending endwise thereof into which extends the reduced inner end of a screw 26 to prevent said member 20 from rotating about its axis.

Between the inner end of the chamber 17 and the inner end of the member 20 is a tubular member 27 having a spring 28 therein between a partition 29 in said tubular member and the inner end of said chamber 20.

Ordinarily this spring 28 is under compression but when the member 20 is being removed from the chamber 17 the spring 28 will immediately commence to expand and

cause the tubular member 27 to follow the member 20 until its forward end comes into contact with the screw 26 when further forward movement is prevented.

5 When the tubular member 27 is in this forward position it closes the passage 16 and prevents the oil in the trough 15 from entering the chamber 17.

The rear end 29 of the member 20 is reduced slightly in diameter and fits into the forward end of the tubular member 27.

When it is desired to remove any sediment which may have collected in the depression 21 of member 20, the closure 19 is removed, a pin or some similar article is positioned in the hole 24, and the member 20 is then withdrawn from the chamber 17 and cleaned.

20 While the member 20 is being cleaned a similar member 20 may be inserted immediately into the chamber 17.

The passage 16 will be closed immediately by the tubular member 27 so that it would be possible to use the motor even 25 while the member 20 was removed.

When cleaned the member 20 is again inserted into the chamber 17 pushing the tubular member 27 into its original position as shown in Fig. 1 and then the closure 19 is 30 screwed into position.

This makes a very simple means whereby the sediment may be removed from the trough 15 without disturbing the trough.

This trough 15 may also be removed when 35 it is desired to make such removal for any good reason.

This is accomplished by removing the bolts 30 extending through the flange 31 formed upon the outer end of the trough 15, 40 said bolts being threaded normally in sockets in the casing 10.

The inner end of the trough 15 is supported on the lug 32.

By this mechanism the troughs may 45 always be kept in condition, free from sediment, as the members 20 may be removed and cleaned as often as desired without placing the engine out of commission.

The invention is particularly adapted for 50 internal combustion engines on fire trucks which should be in condition at all times and ready to respond immediately to any call.

It is believed that the operation and many 55 advantages of the invention will be understood without further description.

Having thus described my invention, I claim:

1. A crank casing provided with a splash 60 trough having a chamber extending longitudinally thereof communicating by means of a passage with the oil compartment thereof located above said chamber; a removable member in said chamber having a sediment 65 collecting pocket normally in register with

said passage; independent means for closing said passage movable endwise in said chamber with said member; and a stop member to limit the movement of said closing means when said passage is closed. 70

2. A crank casing provided with a splash trough having a cylindrical chamber extending longitudinally thereof communicating by means of a passage with the oil compartment thereof; a cylindrical member positioned in said chamber and removable therefrom having a sediment collecting pocket closed at its inner end with its open end normally registering with said passage and provided with a slot in its periphery 80 extending lengthwise thereof; a pin extending into said slot to prevent rotation of said member about its axis; and means for retaining said member in said chamber. 85

3. A crank casing provided with a splash trough having a chamber extending longitudinally thereof communicating by means of a passage with the oil compartment thereof located above said chamber; a member in said chamber having a sediment collecting pocket closed at its inner end with its open end normally in register with said passage and provided at its outer end with a projection of lesser diameter; means preventing the rotation of said member; and a closure 90 threaded to the outer end of said trough adapted to bear upon the end of the body portion of said member to retain it within said chamber, said closure having an opening 95 therein through which said projection extends. 100

4. A crank casing provided with a splash trough having a chamber extending longitudinally thereof communicating by means of a passage with the oil compartment thereof located above said chamber; a removable member in said chamber having a sediment collecting pocket normally in register with said passage; means preventing the rotation of said member; and automatic means within 105 said chamber for closing said passage when said member is removed. 110

5. A crank casing provided with a splash trough having a chamber extending longitudinally thereof communicating by means of a passage with the oil compartment thereof; a removable member in said chamber having a depression normally in register with said passage; a spring pressed element fitting said chamber and adapted to move into position to close said passage upon the removal of said member; and a stop to limit the movement of said element. 115 120

6. A crank casing provided with a splash trough having a chamber extending longitudinally thereof communicating by means of a passage with the oil compartment thereof located above said chamber; a removable member in said chamber having a sediment 125 collecting pocket normally in register with

said passage and provided at its outer end with a cone-shaped surface; means preventing the rotation of said member; a closure for said chamber threaded to said trough and having a socket fitting said member and its cone-shaped surface; and automatic means within and movable endwise of said

chamber for closing said passage when said member is removed.

Signed by me at 746 Old South Bldg., 10 Boston, Mass., this 3rd day of February, 1925.

PARKER B. HASKELL.
